UNITED STATES PATENT OFFICE

2,159,601

REFRIGERATOR SHELF

Carl H. Nauert, Evansville, Ind., assignor to
Servel, Inc., New York, N. Y., a corporation of
Delaware

Application December 12, 1936, Serial No. 115,456

5 Claims. (Cl. 211—153)

My invention relates to shelves and it is an object of my invention to provide an improved shelf for a refrigerator as will appear from the following description and accompanying drawing in which:

Fig. 1 shows a refrigerator having a shelf embodying the invention;

Fig. 2 is a plan view of the shelf alone;

Fig. 3 is a sectional view on line 3—3 in Fig. 2;

Fig. 4 is a plan view of a modification; and

Fig. 5 is a sectional view on line 5—5 of Fig. 4.

Refrigerator shelves must be of open work structure to permit circulation of air in the refrigerator compartment and are usually removable for cleaning purposes. In the refrigerator 10 shown in Fig. 1 the shelves 11 rest on projections such as pegs or hooks on the wall of the storage compartment. One of the shelves 11 is shown in Figs. 2 and 3 and comprises a marginal frame 12 formed by a wire rod bent into the form of a rectangle and butt welded at the ends. A center bar 13 is formed of a length of similar wire rod butt welded at each end to the marginal frame. The wire rod forming the frame may be either round or rectangular in cross section.

This frame structure is well known in refrigerator shelves and is usually covered by a plurality of parallel wire rods, flat strips, or the like which are welded to the frame. In accordance with my invention, however, I make a number of stamped sheet metal elements 14 suitably formed and arranged to be snapped onto the wire rod frame. Each element 14 is stamped from a length of sheet metal which is turned down at each end as at 15 and 15a in Fig. 3 and provided with slots 16 which leave strips 17 and 17a on each side of a center strip 18 and a cross strip 19 in the center of each element. A portion of the metal stamped out to form slots 16 may be retained and turned down to form clips 20 and 21 shown in Fig. 3. The slots 16 are spaced so that the outside strips 17 and 17a are narrower than the central strip 18 so that when a number of elements 14 are arranged side by side on the frame there is obtained the rhythmic appearance shown in United States Design Patent No. 101,136.

A number of elements 14 are secured in spaced parallel relation on the frame by snapping the down turned edges 15 and 15a over the marginal frame bar 12 and the central clips 20 and 21 over the center frame bar 13. To accentuate the rhythmic appearance, the space between the elements 14 should be slightly greater than the width of the slots 16. The sheet metal from which the elements 14 are stamped is preferably thin and resilient so that the elements may be quickly and firmly secured in place as described.

In Figs. 4 and 5 there is illustrated a modified shelf having a similar frame formed by a mar-

ginal rod 12 and a center rod 13. However, instead of forming separate elements as described in connection with Fig. 2, the whole frame covering is stamped from a single sheet of thin resilient metal. In this modification between each two narrow slots 22 there is formed a wider slot 23. The slots 22 are spaced slightly further from each other than from the slots 23 so that there is formed the several groups of two narrow strips 24 and 24a on each side of a wider strip 25. Center clips 26 and 26a are formed out of metal struck out of the slots 22 as previously described. All four edges of the sheet metal shelf cover are turned down as at 27 and 27a in Fig. 5 to be snapped over the marginal frame 12. The four corners of the sheet metal shelf cover are cut away as at 28 in Fig. 4 so that if shelf hooks are used the upturned ends of the hooks may extend through the shelf.

Various changes and modifications will readily occur to those skilled in the art wherefore my invention is not limited to the embodiments shown and described but only as indicated in the following claims.

What is claimed is:

1. A shelf for a refrigerator comprising a rod framework having side rods and a center rod, a sheet metal covering for said framework of resilient material stamped to provide openings for circulation of air therethrough and downturned edges and central projections for resiliently engaging the side rods and center rod respectively of said framework.

2. A shelf for a refrigerator comprising a frame having side rods and a center rod, a plurality of sheet metal elements of resilient material each being stamped to form openings therethrough for passage of air and downturned ends and central projections for resiliently engaging the side rods and center rod respectively of said frame.

3. A shelf for a refrigerator comprising a shelf body of relatively thin material constructed to permit free air circulation within the refrigerator in which the shelf is located, a reinforcing marginal frame for said shelf body, and means operable by the mere act of assembling to positively fasten said body and frame together into a readily removable unit.

4. The structure defined in claim 3 wherein said last mentioned means includes a connection at least a portion of which is yieldable.

5. A shelf for a refrigerator comprising a shelf body of relatively thin material constructed to permit free air circulation, a reinforcing marginal frame for said body, and means operable to positively and detachably fasten said body and frame together into a readily removable unit.
